CATHODE RAY TUBE CIRCUIT

Sterling C. Spielman, Philadelphia, Pa., assignor
to Philco Radio and Television Corporation,
Philadelphia, Pa., a corporation of Delaware

Application March 21, 1940, Serial No. 325,241

12 Claims. (Cl. 250—27)

This invention relates to protective circuits for cathode ray tubes and particularly to improved circuits for preventing damage to the fluorescent screens thereof. The invention is particularly adapted for use in cathode ray television receiving circuits and will be explained with reference to these circuits; however it will be understood that the invention is not restricted to use in television.

The usual cathode ray tube comprises at least an electron emitting cathode, an anode adapted to be supplied with a relatively high positive potential for accelerating the emitted electrons to cause them to impinge upon a fluorescent screen, and a grid which is usually interposed between the cathode and the anode to which may be applied a varying potential to control the intensity of the cathode ray beam. In addition, some means are usually provided for deflecting the cathode ray beam so as to cause it to impinge upon various portions of the fluorescent screen. For example, in a television receiver there are provided horizontal and vertical deflecting circuits which are operated so as to cause the beam to scan the screen in a series of vertically spaced horizontal lines. The high positive potential for supplying the cathode ray tube anode may be obtained by the rectification of power from commercial A. C. sources. Generally, power for the operation of the deflecting circuits will be obtained from the same source by a separate rectifier circuit. In general, the voltage required for the cathode ray tube anode supply will be considerably higher than that required to supply the tubes employed in the deflecting circuits. This being the case, it is observed that the high voltage rectifier circuit is characterized in that the voltage developed thereby persists for some time after the supply of A. C. power to the rectifier has been disconnected. This is generally due to the high time constant of the filter used in connection with the rectifier which cannot conveniently be reduced. The result is that the cathode ray beam persists after the deflecting circuits have ceased functioning. When this occurs, the electrons continue to impinge upon a particular portion of the screen area until the anode voltage decays to a point at which it becomes ineffective to accelerate the electrons sufficiently to cause them to reach the screen. The continued impingement of electrons upon a small area of the screen will cause this area to deteriorate, this effect being commonly referred to as burning.

The principal object of the present invention is to provide means whereby this difficulty may be avoided by automatically cutting off the electron beam as soon as the rectifiers are disconnected from their source of power. By the invention, means are provided for achieving this

end with a minimum of additional apparatus and without appreciably modifying the circuits already used. The invention will now be explained in detail with reference to the drawing 5 in which

Fig. 1 is a diagrammatic illustration of the invention applied to a television receiver; and

Fig. 2 is a similar illustration of another embodiment of the invention.

Referring to Fig. 1, the parts of the receiver which need not be considered in detail for the purposes of this disclosure are represented by the block labeled "Receiver circuits." These may include the radio frequency amplifier supplied with signal from the antenna 1, a converter stage, an intermediate frequency amplifier, a second detector, and a video frequency amplifier and synchronizing signal separator. The detected video signal from these circuits may be supplied to the grid of a final amplifier tube 2, the output circuit of which may be coupled in the manner shown, or in any other suitable way, to the grid of the cathode ray tube 3. The circuit comprising the resistors 4 and 5 and the diode 6 serves to level the signal supplied to the grid of tube 2 and thereby restores the D. C. component lost in previous stages. The separated synchronizing signals from the separating stage may be applied as shown to control the operation of the deflecting circuits, which may be of the conventional form. Voltage for the plate and screen circuits of tube 2 is obtained from the rectifier-filter circuit comprising the diodes 7, the condensers 8 and 9, the choke 10, and the condenser 11. The plates of the diodes, it will be noted, are connected to the secondary of the transformer 12, the primary of which is connected by means of a switch 13 to the A. C. source which may be a 60 cycle line. This rectifier-filter circuit also provides voltage through the connection 14 to the tubes employed in the deflecting circuits. Suitable bias for the cathode ray tube 3 may be obtained from the potentiometer 15. Further, it will be noted that the bypass condenser 16 provided for this potentiometer, instead of being connected to ground, may be connected as shown across the plate filter 17 for the purpose of neutralizing any disturbances engendered in the power supply and appearing across the plate filter. Anode voltage for the tube 3 is obtained from the rectifier comprising the diode 18, the condensers 19 and 20, and the resistors 21 and 22 deriving power through the transformer 23 whose primary is connected 55 through the switch 13 to the A. C. source.

Now it will be noted that upon the removal of power from the rectifier circuits by the opening of the switch 13 the condenser 20 in the cathode ray tube power supply filter will commence to 60 discharge through the bleeder resistor 22,

Hence the time required for the anode potential of tube 3 to reduce itself sufficiently to stop the beam will depend primarily upon the time constant of this RC combination. It is possible, by making this time constant smaller than that of the filter circuit associated with the power supply which supplies the deflecting circuits, to insure cutting off the cathode ray beam before the deflecting circuits cease to function when A. C. power is removed from the rectifier circuits. However in order to do so, it becomes necessary to make resistor 27 of very low resistance and high power-dissipating capability, which is inconvenient and expensive.

According to the present invention, there is provided a novel and simple means for cutting off the cathode ray beam, which eliminates the necessity of modifying the time constant as above-mentioned. By this invention, there is provided a condenser which is charged while the receiver is in operation. When power is removed from the rectifiers, this condenser is connected to one of the electrodes of the cathode ray tube in such a manner that the voltage across the condenser is effective to cut off the cathode ray beam. The condenser may be permitted to discharge at a rate such that the condenser voltage is sufficient at all times to keep the beam cut off until the anode voltage has fallen to such an extent that the beam can no longer exist.

In the embodiment of Fig. 1, the condenser 24 serves this purpose. It will be noted that this condenser is permanently connected to the main power supply through the resistor 25, and to the cathode of tube 3 through the resistor 26. There is also provided a switch 27 in the bias connection to the cathode of tube 3, and this switch is ganged to the power switch 13. When the switch 13 is closed, switch 27 will likewise be closed and the bias on the tube 3 will depend upon the voltage drop across a portion of the potentiometer resistance 15. At the same time, the condenser 24 will be charged through the resistor 25. When power is removed from the rectifiers by opening switch 13, switch 27 will also be opened. Current in the resistor 26 will cease to flow and the cathode of the tube 3 will assume the potential of the condenser 24. The condenser will, of course, discharge through the various resistive paths shunting it. In general, however, the rate of discharge will be determined by the magnitude of resistor 25 which should be large enough to maintain the desired bias upon the tube 3 to cut off the cathode ray beam until the anode potential has been sufficiently reduced.

The following values of circuit elements are exemplary of those which might be used but it will be understood that they are not to be regarded as placing any limitation upon the invention:

Resistor 28	ohms	200,000
Resistor 15	do	47,000
Resistor 25	do	820,000
Resistor 26	do	220,000
Condenser 24	microfarads	4
Condenser 8	do	8
Condenser 20	do	.03
Resistor 22	megohms	30

Referring now to Fig. 2, there is shown another embodiment of the invention in which a different arrangement of the circuit is used to effect the charging of the biasing condenser and to connect it to an element of the cathode ray tube when power is removed. In this circuit, a

different mode of coupling is employed between the amplifier tube 2 and the cathode ray tube 3. The load impedance for tube 2 comprises the resistors 29 and 30 and the inductance 31 shunting the latter. The plate supply is from the rectifiers 7, as before. An A. C. coupling including the condenser 32, the peaking coil 33, and the damping resistor 34 is provided between the plate of tube 2 and the grid of the cathode ray tube 3. Of course it is essential also to transmit the D. C. component to the grid of the picture tube. In the present instance, this is done by two connections, one of which supplies the D. C. component developed across the resistor 35 to the cathode of the picture tube, while the other connection is from the screen grid of tube 2 via the potentiometer 36 to the grid of the picture tube. It will be noted that the resistor 35 is bypassed by the condenser 37 for A. C. and also that provision is made for controlling gain by the inclusion of the potentiometer 38 and condenser 39 whereby the degeneration of the tube 2 may be varied. The resistor 40 is large by comparison with the resistor 35 and its effect is unimportant except when switch 41 is open. The rest of the circuit is similar to that of Fig. 1 and need not again be discussed.

Upon the closing of the power switch 13, switch 41 which is ganged thereto is also closed so as to include the resistor 35 in the circuit. The condenser 39 will be charged by the flow of current in the tube 2. It has been found that the potential assumed by this condenser is sufficient, when applied to the cathode of a picture tube, to bias off the cathode ray beam therein. This obtains when the switch 41 is opened upon the removal of power from the circuit. At this time, the current in the resistor 42 is greatly reduced and the potential applied to the cathode of tube 3 through the connection 43 is substantially that across the condenser 39. Resistor 40 which is provided to discharge the condenser should be sufficiently large to do so at a relatively slow rate compared to that of the discharge of condenser 20 through the bleeder 22 in the anode supply to tube 3. Thus, condenser 39 serves not only in conjunction with potentiometer 38 to regulate degeneration in tube 2, but also serves to develop the required voltage for cutting off the cathode ray beam in accordance with the invention.

The following values are given as exemplary in the circuit of Fig. 2 but are not to be regarded as restrictive of the invention:

55 Resistor 35	ohms	10,000
Condenser 37	microfarads	40
Resistor 40	megohms	0.47
Resistor 42	ohms	3300
Resistor 38	do	5000
60 Condenser 39	microfarads	40
Condenser 20	do	0.06
Resistor 22	megohms	15

It will be apparent that other embodiments of the invention are possible and the invention is to be regarded as limited only by the scope of the appended claims.

I claim:

1. In a cathode ray tube system, a cathode ray tube having an electron beam-emitting means, a beam-sustaining electrode and a control element, means for supplying a beam-sustaining potential to said electrode, a space discharge device arranged to receive control energy and supply the same to said control element, means in

the cathode circuit of said space discharge device for controlling the output thereof, said last-named means including a condenser across which a voltage is established, and means for applying said condenser voltage to said cathode ray tube so as to reduce materially the intensity of the electron beam whenever said potential-supply means is rendered inoperative, thereby to render ineffective any residual potential remaining on said electrode.

2. In a cathode ray tube circuit; a cathode ray tube comprising a cathode, an anode, and a control grid adapted to cooperate in the formation and control of a cathode ray beam; a source of power; means for adapting power from said source to provide anode voltage for said tube, said means being characterized in that the voltage provided thereby persists for a time after the disconnection of said means from said source; a switch for connecting said means to said source; a condenser; means for charging said condenser whenever said means is connected to said source for developing across said condenser a voltage which, when applied to one of the electrodes of said cathode ray tube, is effective to cut off said cathode ray beam; means for applying a relatively small fraction of said condenser voltage to said electrode when said power adapting means is connected to said source; and means for applying a larger fraction of said condenser voltage to said electrode when said power adapting means is disconnected from said source.

3. In a cathode ray tube circuit; a cathode ray tube comprising a cathode, an anode, and a control grid adapted to cooperate in the formation and control of a cathode ray beam; a source of power; means for adapting power from said source to provide anode voltage for said tube, said means being characterized in that the voltage provided thereby persists for a time after the disconnection of said means from said source; a switch for connecting said means to said source; a condenser; means for charging said condenser whenever said means is connected to said source for developing across said condenser a voltage which, when applied to one of the electrodes of said cathode ray tube, is effective materially to reduce the intensity of said cathode ray beam; means for applying a relatively small fraction of said condenser voltage to said electrode when said power adapting means is connected to said source; and means for applying a larger fraction of said condenser voltage to said electrode when said power adapting means is disconnected from said source.

4. In a cathode ray tube circuit; a cathode ray tube comprising a cathode, an anode, and a control grid adapted to cooperate in the formation and control of a cathode ray beam; a source of power; means for adapting power from said source to provide anode voltage for said tube, said means being characterized in that the voltage provided thereby persists for a time after the disconnection of said means from said source; a switch for connecting said means to said source; a condenser; means for charging said condenser whenever said power adapting means is connected to said source for developing across said condenser a voltage which, when applied to one of the electrodes of said cathode ray tube, is effective materially to reduce the intensity of said cathode ray beam; a voltage divider connected to said condenser; means for connecting said electrode to a point on said voltage divider when said power adapting means is connected to said source

to apply a relatively small fraction of the voltage across said condenser to said electrode; and means for connecting said electrode to a different point on said voltage divider when said power adapting means is disconnected from said source to apply a larger fraction of said condenser voltage to said electrode.

5. In a cathode ray tube circuit; a cathode ray tube comprising a cathode, an anode, and a control grid adapted to cooperate in the formation and control of a cathode ray beam; a source of power; means for adapting power from said source to provide anode voltage for said tube, said means being characterized in that said anode voltage decays slowly upon the disconnection of said means from said source; a switch for connecting said means to said source; a condenser; means for charging said condenser whenever said power adapting means is connected to said source for developing across said condenser a voltage which, when applied to one of the electrodes of said cathode ray tube, is effective materially to reduce the intensity of said cathode ray beam; means for applying a relatively small fraction of said condenser voltage to said electrode when said power adapting means is connected to said source; means for applying a larger fraction of said condenser voltage to said electrode when said power adapting means is disconnected from said source; and means for discharging said condenser at a rate such as to maintain said cathode ray beam at substantially reduced intensity during the decay of said anode voltage.

6. In a cathode ray tube circuit; a cathode ray tube comprising a cathode, an anode, and a control grid adapted to cooperate in the formation and control of a cathode ray beam; a source of alternating current; means for rectifying said alternating current to provide anode voltage for said cathode ray tube, said means including a filter circuit having large time constant; a switch for connecting said means to said source; a condenser; means for utilizing a portion of the rectified current to charge said condenser whenever said rectifying means is connected to said source, for developing across said condenser a voltage which, when applied to one of the electrodes of said cathode ray tube, is effective materially to reduce the intensity of said cathode ray beam; means for applying a relatively small fraction of said condenser voltage to said electrode when said rectifying means is connected to said source; means for applying a larger fraction of said condenser voltage to said electrode when said rectifying means is disconnected from said source; and means for discharging said condenser at a rate such as to maintain said cathode ray beam at substantially reduced intensity during the decay of said anode voltage.

60 7. In a cathode ray tube circuit, a cathode ray tube having an electron beam-emitting means and a beam-sustaining electrode, means for supplying a beam-sustaining potential to said electrode, a condenser, means for charging said condenser whenever said potential-supply means is operative, thereby to develop a voltage across said condenser, means for applying a relatively small fraction of said condenser voltage to said tube to maintain said electron beam at a desired operating intensity when said potential-supply means is operative, and means for applying a larger fraction of said condenser voltage to said tube to substantially reduce the intensity of said beam when said potential-supply means is rendered inopera-

4
tive, thereby to render ineffective any residual potential remaining on said electrode.

8. In a cathode ray tube circuit, a cathode ray tube having an electron beam-emitting means and a beam-sustaining electrode, means for supplying a beam-sustaining potential to said electrode, a condenser, means for charging said condenser whenever said potential-supply means is operative, thereby to develop a voltage across said condenser, means for applying a relatively small fraction of said condenser voltage to said tube to maintain said electron beam at a desired operating intensity when said potential-supply means is operative, means for applying a larger fraction of said condenser voltage to said tube to substantially reduce the intensity of said beam when said potential-supply means is rendered inoperative, thereby to render ineffective any residual potential remaining on said electrode, and means for discharging said condenser at a rate appreciably less than the rate at which said residual potential is reduced.

9. In a cathode ray tube system, a cathode ray tube having an electron beam-emitting means, a beam-sustaining electrode and a control element, means for supplying a beam-sustaining potential to said electrode, a space discharge device arranged to receive control energy and supply the same to said control element, means in the cathode circuit of said space discharge device for controlling the output thereof, said last-named means including a condenser across which a voltage is established, means for applying a relatively small fraction of said condenser voltage to said tube when said potential-supply means is operative, and means for applying a larger fraction of said condenser voltage to said tube when said potential-supply means is rendered inoperative, thereby to render ineffective any residual potential remaining on said electrode.

10. In a cathode ray tube circuit, a cathode ray tube having an electron beam-emitting means and a beam-sustaining electrode, means for supplying a beam-sustaining potential to said electrode, a condenser, means for charging said condenser whenever said potential-supply means is operative, thereby to develop a voltage across said condenser, a voltage divider connected in shunt with said condenser, a connection from said voltage divider to said cathode for applying a

5 fraction of the voltage thereacross to said cathode whenever said potential-supply means is operative, and means for modifying the impedance of said divider whenever said potential-supply means is inoperative, to thereby apply a larger voltage to said cathode.

11. In a cathode ray tube circuit, a cathode ray tube having an electron beam-emitting means and a beam-sustaining electrode, means for supplying a beam-sustaining potential to said electrode, switching means for controlling said potential-supply means, a condenser, means for charging said condenser when said potential-supply means is operative, thereby to develop a voltage across said condenser, connections for applying said condenser voltage to said tube to control the electron beam, and switching means operable conjointly with said first-mentioned switching means to modify the effectiveness of said connections and thereby control the application of said condenser voltage to said tube.

12. In a cathode ray tube circuit, a cathode ray tube having an electron beam-emitting means, a beam-sustaining electrode and a beam-controlling electrode, means for supplying a beam-sustaining voltage to said beam-sustaining electrode, said last-named means comprising a source of power, a rectifying device and filter means, means for supplying a beam-controlling voltage to said beam-controlling electrode, said last-named means comprising a source of power, a rectifying device and filter means, said last-named filter means normally having a time constant smaller than the time constant of said first-named filter means, means for applying a relatively small fraction of the voltage developed by said controlling voltage supply means to said beam-controlling means during normal operation, and means for modifying the constitution of said last-named filter means in response to the disconnection of said first-named power source from said first-named rectifying device, to thereby apply a relatively larger fraction of the voltage developed by said controlling voltage supply means to said beam-controlling electrode and to render the time constant of said last-named filter means greater than the time constant of said first-named filter means.

50 STERLING C. SPIELMAN.
